UNITED STATES PATENT OFFICE.

SAMUEL T. MONTROSE, OF NEW YORK, N. Y., ASSIGNOR OF ONE-HALF TO CURTIS R. BURNETT AND ONE-FOURTH TO ALFRED MONTROSE, OF NEWARK, NEW JERSEY.

LOCK.

No. 853,717.

Specification of Letters Patent.

Patented May 14, 1907.

Application filed April 6, 1906. Serial No. 810,212.

To all whom it may concern:

Be it known that I, SAMUEL T. MONTROSE, a citizen of the United States of America, and a resident of the borough of Manhattan, 5 city, county, and State of New York, have invented certain new and useful Improvements in Locks, of which the following is a specification.

The present invention relates to locks, 10 and has for its object the production of means rendering the picking of the lock extremely difficult, if not impossible. To this end the invention is characterized by two latches adapted to move in curvilinear paths and having intermeshing teeth so as 15 to move in unison.

Other features of construction and combination of parts will appear as the specification proceeds.

20 In the accompanying drawings the invention is illustrated in a concrete and preferred form, but changes of construction may of course be made and parts omitted without departing from the spirit of the invention.

25 In the said drawings: Figure 1 is a general view of a lock and door jamb with the parts exposed showing the latch mechanism in its closed position and locked against retraction, embodying the invention. Fig. 2 is a 30 view similar to Fig. 1, but showing the locking device released from the latch mechanism. Fig. 3 shows the latch mechanism withdrawn. Fig. 4 is a detached view of the door jamb. Fig. 5 is a detail view in perspective of the sleeve through which the key 35 is inserted. Fig. 6 is a detail view of the key.

Similar characters of reference indicate corresponding parts in the different views.

40 1 indicates a casing of any suitable construction in which is arranged the latch mechanism 2. Abutting the casing on one side is the door jamb 3. This door jamb is obliquely recessed by being provided preferably with two divergent curvilinear slots 4 and 5. The latch mechanism travels in an oblique path and consists preferably of two latches 6 and 7 moving in divergent curvilinear paths to engage and disengage 45 with the slots in the door jamb. The spring 8 engaging with the pin 9 normally keeps the latch mechanism in its closed position. In order that the two latches may move in unison in the same direction back and forth,

there are provided intermeshing teeth 10 55 on the said two latches, whereby the movement of one causes a corresponding movement of the other.

11 denotes a locking device pivoted at 12 on the casing. This locking device is provided with a slot 13 having a recessed inclined locking surface 14 adapted to engage with the pin or member 15 on the latch mechanism when the latter is in its closed position. A spring 16 normally keeps the locking surface in engagement with the pin 15 on the latch mechanism when the latter is in its closed position. It will be noticed that the parts when in this position are locked, and that the latch mechanism can neither 70 be worked out of the slots in the door jamb nor can the latter be sprung away from the latch mechanism as the oblique surfaces of the slots in the jamb and the corresponding surfaces of the latch mechanism are wedged 75 together by reason of the inclined locking surface on the locking device.

The latch mechanism can be withdrawn from one side of the lock (the inside) by means of the rotatable spindle 17 which extends 80 through the casing and through one of the latches. On this spindle is mounted the dog 18, which, when the spindle is turned, releases the locking device and latch mechanism from each other as shown in Fig. 2. This spindle is 85 capable of a movement sidewise with the latch mechanism by reason of the slot 19 in the casing so that a subsequent sidewise movement of the said spindle will withdraw the latch mechanism, the pin 15 sliding through the slot 90 13 in the locking device. By allowing the dog 18 to engage with the notch 19^a of the locking device the latch mechanism will be held in its open position as shown in Fig. 3. A second notch 20 is provided in the locking device 95 whereby when the dog 18 engages this the locking device will be in a position released from the latch mechanism, but the latter will not be withdrawn. When in this position, the closing of the door will cause the latch 100 mechanism to move back thereby releasing the dog from the locking device, and, when the latches coincide with the slots in the door jamb, they will shoot into engagement therewith and the locking device will move into 105 position to lock them against retraction. The dog 18 is held normally out of engagement with the locking device by means of the

spring 21. The latch mechanism can be retracted from the other side of the lock (the outside) by means of the key 22. This key is of a peculiar construction, being provided with the bit 23 pivoted at 24 and normally held in the position shown in Fig. 6 by means of the spring 25. In this position, the comb is almost in alignment with the spindle of the key. Extending through the casing from the outside is the sleeve 26 provided at one point with a cut out portion 26^a whereby a ledge 27 is formed. If the key is inserted through this sleeve the bit thereof will be held in alignment with the spindle thereof until the cut out 26^a is reached when the spring 25 will turn the bit slightly whereby the ledge 27 will be encountered, and the bit will be turned at right angles to the spindle. By turning the key, the latter will first engage the locking device thereby releasing it from the latch mechanism. The key will then encounter the shoulder 28 on the latch mechanism, and the latter will be withdrawn. Of course any number of shoulders may be employed, and a corresponding number of surfaces on the key may be provided.

What is claimed is:

1. In a lock, two latches moving in curvilinear paths, and intermeshing teeth on the said latches whereby they move in unison.
2. In a lock, a door jamb having curvilinear slots, two latches moving in curvilinear paths into and out of engagement with the slots aforesaid, intermeshing teeth on the said latches, means for preventing the retraction of the latches, and means which when operated act progressively to release the locking means and to retract the latches.
3. In a lock, a door jamb having curvilinear slots, two latches moving in curvilinear paths into and out of engagement with the slots aforesaid, intermeshing teeth on the said latches, a member on the latch mechanism, a locking device adapted to engage the said member when the latch mechanism is in its closed position, and means for releasing the locking device and for retracting the latch mechanism from both sides of the door.
4. In a lock, a door jamb having two curvilinear slots, two latches moving in curvilinear paths into and out of engagement with the slots, intermeshing teeth on the latches, a locking device for the latch mechanism preventing its retraction, and means for releasing the locking device and retracting the latch mechanism from either side of the door.
5. In a lock, two latches adapted to move in curvilinear paths, intermeshing teeth on the said latches, means for operating one of the latches from side of the door, and means for operating the other of said latches from

the other side of the door, whereby both latches can be moved in unison from either side of the door.

6. In a lock, a door jamb having two curvilinear slots, two latches adapted to move in curvilinear paths into and out of engagement with the slots, intermeshing teeth on the said latches a member on the latch mechanism, a locking device adapted to engage with the member on the latch mechanism when the latter is in its closed position, a dog capable of a rotary movement independent of the latch mechanism and a sidewise movement with the latch mechanism, which acts, when rotated to lift the locking device thereby releasing the latch mechanism from the locking device and when moved sidewise to retract the latches.

7. In a lock, the combination of two latches moving in curvilinear and divergent paths, intermeshing teeth on the said latches whereby they move in unison, a locking member stationarily supported having a slot with a recessed portion, a member on one of the latches normally in engagement with the recessed portion of the slot aforesaid when the latches are in their closed position,

means for normally keeping the latches in their closed position, a rotatable spindle extending from the outside of the lock through one of the latches and slidably movable therewith, and a dog mounted on the said spindle, whereby the rotation of the said spindle causes the dog to engage with the locking member thereby releasing the member carried by one of the latches from the recess in the slot, and whereby a subsequent sidewise movement of the spindle causes the withdrawal of the latches.

8. In a lock, the combination of a door jamb having two oblique slots, two latches moving in unison in oblique paths into engagement with the slots aforesaid, a member on the latch mechanism, a locking device adapted to engage with the member on the latch mechanism when the latter is in its closed position, a dog capable of a rotary movement independent of the latch mechanism and a sidewise movement with the latch mechanism, which acts, when rotated to lift the locking device thereby releasing the latch mechanism from the locking device, and when moved sidewise to retract the latches, and a shoulder on the locking device adapted to engage with the dog to hold the latch mechanism in its retracted position.

Signed at New York this 14th day of March, 1906.
